UNITED STATES PATENT OFFICE.

JOHN L. DABADIE, OF ANGELS CAMP, CALIFORNIA.

TUBING FOR TIRES FOR MOTOR-VEHICLES.

1,115,907.

Specification of Letters Patent.

Patented Nov. 3, 1914.

Application filed March 20, 1913. Serial No. 755,620.

To all whom it may concern:

Be it known that I, JOHN L. DABADIE, a citizen of the United States, residing at Angels Camp, county of Calaveras, State of California, have invented certain new and useful Improvements in Tubing for Tires for Motor-Vehicles; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in tires for motor vehicles and is adapted to provide an inner tubing for the outer casings of said tires which will not necessitate the use of air to give the necessary resiliency or cushion effect of pneumatic tires, but at the same time will give the resiliency equal to or greater than that of air and which will take up and compensate for all the jolts or jars encountered on the road's surface. This structure will do away with the objectionable features of pneumatic tires such as blow-outs, punctures, the necessity of inflating the same and all the other numerous incidents to the use of such pneumatic tires.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings similar characters of reference indicate corresponding parts in the several views.

Figure 1 is a sectional view of a portion of my improved inner tubing. Fig. 2 is a cross sectional view of the inner tubing shown within the outer casing. Fig. 3 is a longitudinal section of a portion of the inner tubing showing the mechanism for expanding the same against the outer casing.

Fig. 4 is a top plan view of the structure shown in Fig. 3 with the spring and casing removed. Fig. 5 is a side elevation of my improved structure partly broken out showing the inner tubing prior to expansion.

Referring now more particularly to the characters of reference on the drawings, the

numeral 1 designates the felly of a wheel and the numeral 2 the casing adapted to receive my improved inner tubing, which outer casing is of the same design as those now ordinarily used on all pneumatic tires now on the market, in all sizes, no special casing being required. In providing my improved inner tubing I form the same of sheet steel divided into sections, each section comprising an upper member 3 and a lower member 4. Each of the members 3 and 4 is provided with cross braces 3^a and 4^a respectively to prevent any tendency of these members 3 and 4 to bulge laterally. The upper members of every other section are provided at each end with castings or plates 5 and the corresponding lower members with castings or plates 6, which castings or plates 5 and 6 are riveted to their respective members and adapted to slidably project into the adjacent members of the intermediate section and not fastened thereto, such intermediate section being then held normally in position by means of a plurality of springs 7, two of said springs crossing each other and being connected to the plates 5 and 6 as shown in Fig. 1, which structure permits the said sections to be moved slidably apart but still be held in position relative to the plates 5 and 6.

Each of the plates 5 is provided with a fixed receptacle 8. Mounted on threaded pins 12 are similar recessed receptacles 10. A spring 11 is interposed between each pair of the receptacles 8 and 10, the pin 12 projecting through the central parts of the springs 11. The lower end of the pin 12 is then journaled in a member 13 on the plate 6 and mounted on the same is a worm gear 14, which worm gear is intermeshed with another worm gear 15 mounted on a shaft 16 journaled in members 17 on the plate 6. On each end of the shaft 16 is a universal joint 18, each pair of universal joints on each section being then connected by pins 19 with corresponding or similar universal joints on the next section and then, this same structure is repeated continuously around the entire tubing.

As will be seen, the upper series of the members 3 are capable of movement vertically with respect to the lower series 4 and the springs 11 being interposed between the same give the necessary resiliency. The adjacent members on each section are capable of moving circumferentially with respect to

each other and are given a resiliency and are held together by the springs 7. The whole is then held together in close contact with the outer casing 2 and within the same 5 by means of the following structure, namely: A pin 20 projects through the felly 1 at one point and is provided with a square outer end 21 and on its inner end has a worm gear 22 intermeshing with a worm gear 23 10 on one of the shafts 16. Hence, by turning the pin 20, this turns the worm gear 22, the worm gear 23 and shaft 16 which, by means of the universal joints and connections just described, turns all of the shafts 16 in the 15 entire tubing. Incidentally this turns all of the worm gears 15 and all of the worm gears 16, which turns all of the pins 12 and since said pins are threaded through the members 10 this causes the members 10 to move up 20 wardly and compress the springs 11. The tension of such springs will then tend to force the members 3 and 4 outwardly and circumferentially and will cause the same to engage the inside of the casing 2 in a strong 25 frictional grip.

This structure makes the complete tire for the wheel of the vehicle and as will be readily seen it provides a resiliency within an outer casing similar to the inner pneumatic tubing, but stripped of all the objections to be noted in the use of such pneumatic tubing. For the purpose of taking the tire down, the above described operation would of course be reversed. To permit of 30 the separating operation above described, the pins 19 are, of course, square and are fixed rigidly to one of the universal joints as at 35 19^a and are slidably disposed within the other.

40 From the foregoing description it will be readily seen that I have produced such a device as substantially fulfills the objects of the invention as set forth herein.

While this specification sets forth in de-

tail the present and preferred construction 45 of the device, still in practice such deviations from such detail may be resorted to as do not form a departure from the spirit of the invention.

Having thus described my invention what 50 I claim as new and useful and desire to secure by Letters Patent is:

1. A device of the character described comprising a tubing consisting of sections, each section consisting of two parts, said 55 sections being adapted to be suitably joined, a turnable pin on one part of each section, a screw member mounted on said pin, a resilient member disposed between said member on said pin and the other part of said 60 section, a pinion on said turnable pin, a worm gear engaging said pinion, a pin connected with said worm gear, a pinion on said pin, a worm gear engaging said last named pinion, and a pin on said last named worm 65 gear projecting outside of said tubing, as described.

2. A device of the character described comprising a tubing consisting of sections, each section consisting of two parts, said 70 sections being adapted to be suitably joined, a turnable pin on one part of each section, a screw member mounted on said pin, a resilient member disposed between said member on said pin and the other part of said 75 section, a pinion on said turnable pin, a worm gear engaging said pinion, a pin on each of said worm gears, universal joints connecting all of said last named pins within the tubing, and an operating means for 80 turning one of said last named pins, as described.

In testimony whereof I affix my signature in presence of two witnesses.

JOHN L. DABADIE.
